(57) **CLAIM**

The ornamental design for a hair clipper, as shown and described.

DESCRIPTION

FIG. 1.1 is a perspective view of a new design for a hair clipper.

FIG. 1.2 is a back view of a new design for a hair clipper.

FIG. 1.3 is a left view of a new design for a hair clipper.

FIG. 1.4 is a top view of a new design for a hair clipper.

FIG. 1.5 is a right view of a new design for a hair clipper.

FIG. 1.6 is a bottom view of a new design for a hair clipper.

FIG. 1.7 is a front view of a new design for a hair clipper. The broken lines depicting a blade portion are for environmental purposes and form no part of the claimed design.
